Attest.

UNITED STATES PATENT OFFICE.

CARL E. BAUER, OF HAMMOND, INDIANA.

BRAKE-BEAM FULCRUM AND METHOD OF PRODUCING SAME.

1,402,392.

Specification of Letters Patent. Patented Jan. 3, 1922.

Application filed September 16, 1920. Serial No. 410,722.

To all whom it may concern:

Be it known that I, CARL E. BAUER, a citizen of the United States, and resident of Hammond, in the county of Lake and State 5 of Indiana, have invented certain new and useful Improvements in a Brake-Beam Fulcrum and Method of Producing the Same, of which the following is a specification.

My invention relates to brake beam ful- 10 crums and particularly to a novel method of forging or forming such fulcrums.

It will be understood that a fulcrum or strut is employed in the construction of 15 brake beams the device serving, as its name implies, as a fulcrum for the brake lever, and, in-trussed beams, as a strut for separating the compression and tension members.

It is to the type last referred to that this 20 improvement particularly relates. It is common to employ fulcrums composed of a bar doubled upon itself and provided with lateral projections or feet at the free ends of the bar and with a saddle at the opposite end, the saddle serving as a seat for the 25 tension rod, the feet being secured by riveting to the channel of the compression member. It is to the formation of the saddle or seat in the bar that this invention particularly relates.

30 An object in the present invention is to simplify the formation of this saddle, increase its strength and lessen the cost and number of operations necessary to produce it. The fulcrum is formed by two major die operations in the first of which a plain 35 rectangular bar is pressed at a point intermediate its ends and thereby flared; in the second, the seat or saddle is formed after the bar has been doubled upon itself on the 40 line of the flattened portion. In these operations the cross sectional area of the bar remains substantially constant; in other words, in the flattening operation the bar is merely deflected laterally and is not elongated.

45 In this way a saddle of great strength is provided and one in which the area of contact with the tension rod is considerable. The novel fulcrum and the method of forming it will be better understood by 50 reference to the accompanying drawings, in which,

Figs. 1 and 2 are plan and side views respectively of a bar or blank such as I employ;

55 Figs. 3 and 4 are plan and side views re-

spectively of the blank after the first die operation;

Figs. 5 and 6 are plan and side views respectively of the die within which the operation of flattening illustrated in Figs. 3 and 4 is carried out;

Figs. 7 and 8 are end and side views respectively of the fulcrum after it has been doubled upon itself;

Figs. 9 and 10 are similar views showing 65 the fulcrum after the third operation thereon;

Figs. 11 and 12 are plan and side views of 70 the dies within which the operation of forming the seat is carried out;

Fig. 13 is a perspective view of the fulcrum in its completed form;

Figs. 14 and 15 are end and side views 75 respectively of the same fulcrum in which the seat is formed at right angles to the normal plane of the bar, and,

Figs. 16 and 17 are similar views in which a flat instead of a round tension rod is employed.

In the drawings it will be seen that the 80 fulcrum comprises two arms 20, 21, having lateral projections or feet 22, 23, which serve as the means of attachment of the fulcrum to the compression member of a beam. A saddle or seat 24, is formed in the fulcrum 85 at its doubled-up end and this constitutes the gist of this invention. In forming the fulcrum I prefer to take a flat bar, preferably rectangular in cross section as shown in Figs. 1 and 2. This bar is placed in a die 90 25, shown in Figs. 5 and 6, and the ends of the bar may be suitably confined. A complementary die member 26, is then forced down against the bar and it is flattened or laterally expanded as at 27, in Figs. 3 and 95 5. This, as shown in Fig. 4, effects a decrease in the thickness of the bar but the cross sectional area of the bar remains substantially constant throughout.

In the next operation the blank is doubled 100 upon itself, as best shown in Figs. 7 and 8, and this may be carried out in any common bending machine. This results in the formation of a straight, wide center portion 28, as best shown in Fig. 8. In the next 105 operation, the thus-formed blank is placed upon a die 29, shaped as best shown in Figs. 11 and 12, and a complementary die 30, is forced into engagement therewith. The angular position of the die 30, which position 110

may readily be changed as required, determines the angularity of the seat relative to the plane of the side members 20, 21, of the fulcrum. These two die members 29, 5 30, serve to form a seat, the lateral portions of which constitute retaining lips. The metal constituting the seat having been pressed and densified, is strong and rigid and gives the necessary rigidity to the beam 10 of which it forms a part. There is no waste metal as all the parts of the seat cooperate, due to the peculiar shape and disposition of the metal.

In event a fulcrum is to be formed in 15 which the brake lever lies at right angles to the beam, the die 30 is moved until it lies at an angle of 90° to the die 29. This results in the formation of the fulcrum shown in Figs. 14 and 15, in which the seat 20 31 is directly transverse to the side bars 32.

In the construction of Figs. 16 and 17 this same situation prevails. I have, however, shown a flat tension member 33, instead of a round rod as in the preceding 25 figures.

Obviously the construction and method are capable of some modification and I do not wish to be limited except as indicated in the appended claims.

30 I claim:

1. The method of forming a brake beam fulcrum, consisting in providing a blank, widening a portion thereof, bending said

blank at the widened portion and forming a seat in said widened portion.

35

2. The method of forming a brake beam fulcrum, consisting in providing a blank, widening a portion thereof, bending said blank at the widened portion, and drawing the widened portion in a given direction to 40 form a seat thereon.

3. The method of forming a brake beam fulcrum, consisting in providing a blank, widening a portion thereof, bending the blank at said widened portion and spreading the widened portion of the metal to 45 form a seat.

4. A brake beam fulcrum, consisting of a bar doubled upon itself and having a forged saddle, the cross sectional area of 50 the bar in its completed form being substantially constant throughout its length.

5. A brake beam fulcrum comprising a blank, a portion of which is spread in the plane of the blank and also in an intersecting 55 plane to form a seat.

6. A fulcrum composed of a bar doubled upon itself and provided at its free ends with means of attachment to a beam and at the opposite end with a saddle formed by 60 pressing the bar laterally and thereby thinning it and then forming retaining lips.

Signed at Chicago, Ill., this 14th day of September, 1920.

CARL E. BAUER.
